UNITED STATES PATENT OFFICE.

ARTHUR J. BRIGGS, OF SYRACUSE, NEW YORK, ASSIGNOR TO NATIONAL CARBON COMPANY, INC., A CORPORATION OF NEW YORK.

ELECTRICAL SWITCH.

Application filed May 20, 1922. Serial No. 562,421.

This invention relates to improvements in electrical switch mechanism. The invention has particular reference to devices of the "three-position" type, in which a circuit controlling member, normally freely movable into or out of operative position, may be secured in either of such positions by actuation of suitable locking means. Three-position switches are applicable in general 10 to electrical apparatus in which it is desirable, under varying requirements of operation, to effect an easy intermittent closure of the circuit or to securely retain the same for relatively extended periods in open or closed condition. For purposes of illustration, the switch mechanism of the present invention will be described in connection with a portable battery operated hand lamp.

It is an object of this invention to provide 20 a simple and rugged switch construction, capable of easy movement into any of its adjusted positions. The construction comprises broadly a resiliently mounted contact member, normally freely compressible to engage a conductor strip, and a slide adapted to be inserted either beneath or above a portion of the contact member, to prevent it from being depressed and to hold it in depressed position, respectively.

30 In the preferred form of my invention, a conductor strip is carried by the switch mechanism. Attachment of the latter to the casing serves also to secure the conductor strip in operative position, without 35 the necessity of riveting the strip to the casing as in usual practice.

A preferred embodiment of the invention will be described in detail in connection with the accompanying drawings, in 40 which—

Fig. 1 is an elevation of a tubular flashlight provided with the improved switch,

Fig. 2 is a longitudinal section on line 2—2, Fig. 1, showing the switch in intermittently operable position,

Fig. 3 is a transverse section on line 3—3, Fig. 2, on an enlarged scale,

Figs. 4 and 5 are enlarged longitudinal sectional views through the switch, showing it respectively in open and closed locked positions, and

Fig. 6 is a plan view of the locking slide.

Referring to the drawings, reference numeral 1 denotes a tubular flashlight casing having an escutcheon plate 2 secured

over an opening therein by rivets 3 or other suitable means. An elongated housing 4, preferably integral with the escutcheon plate has a circular perforation 5 adjacent one end. A push button 6, mounted on a resilient arm 7, is vertically movable through the perforation. Arm 7 is attached to the opposite end of the housing 4 by a rivet 8, which also secures a bracket 9 to the housing. The elongated arm 10 of the bracket 9 lies beneath and is parallel to the housing. An inwardly extended plate 11 preferably formed integrally with the arm 10, is secured by rivet 11' to the end of the housing opposite to that at which the bracket 7 is attached.

A stirrup-shaped slide 12 is received within the housing and is adapted to be supported by bracket arm 10 and plate 11. The slide 12 has a limited reciprocating travel 75 between the end of the housing and the downwardly turned portion of bracket 9. Motion may be imparted to the slide by means of fingerpiece 13 riveted to its base and movable in a longitudinal slot 14 in the cover of housing 4. An upturned spring arm 15, secured to the base of slide 5, has a rounded end 16 adapted to be snapped into rounded elevations 17 and 18 on the housing cover, to hold the slide in either of its extreme positions. The resilient arm 7 is slotted at 19 to permit the travel of fingerpiece 13 and the passage of the end 16 into the elevations.

The lateral portions 20 and 21 of the bracket arm 10 may be bent inwardly to clamp a conductor strip 22, which is encased in insulating material 23. One end of the strip underlies the push button 6 and is curved upwardly to provide a resilient seat 24 for rounded contact member 25 carried by the button. The other end 26 of the strip extends beyond the housing and is of such length as to engage a conductive disk affixed to the insulated reflector, as shown in Fig. 2.

The operation of the switch is as follows: The intermittently operable adjustment is obtained by moving the finger piece 13 toward the center of the housing, from the position illustrated in Fig. 4, until spring end 16 snaps into elevation 17. Such movement places the arched end of stirrup-shaped slide 12 adjacent the wall of the housing (Fig. 2), and the push button can be depressed past the slide into engagement

with seat 24 on conductor strip 22. To lock the button out of contact, finger piece 13 is returned to the position shown in Fig. 4, in which the slide is interposed between the button and the strip. Continuous contact is obtained by placing the device in intermittently operable position, depressing the button, and moving the slide 12 to the position shown in Fig. 5, in which it overlies the projecting end of resilient arm 7 and retains the same in depressed position.

In the form of the invention illustrated herein, a metal flashlight casing is provided and the reflector is insulated therefrom. It will be seen that the attachment of the metal switch housing to the casing, in such manner that the insulated conductor strip is in contact with the reflector, is the single operation necessary to establish the electrical circuit. The elimination of separately attached conductor strips results in materially facilitating assembly. If a fiber casing is used, it will be necessary to connect the zinc terminal of the battery with the lower end of the switch structure.

The improved switch mechanism is of course in no way restricted to use with a conductor strip attached thereto. Such strips may be riveted to the casing in the usual or any suitable manner and the switch mounted to cooperate therewith. Various other changes in the specific embodiment described herein may be made within the scope of the appended claims.

I claim:—

1. An electrical switch comprising a reciprocable member having an opening therethrough, a resiliently mounted contact depressible through said opening in one position of said member to engage a conductor, said member being movable to other positions to prevent depression of the contact and to hold the contact continuously depressed.

2. An electrical switch comprising a housing, a resiliently mounted push button carrying a contact depressible with respect to said housing to engage a conductor, and a slide, adjustable in the housing and having an opening therethrough, said slide being adapted in one adjusted position to permit depression of the push button to bring the contact into engagement with a conductor, adapted in another adjusted position to overlie a portion of the button, and in another adjusted position to underlie a portion of the same, whereby the contact may be locked in either operative or inoperative position.

3. The invention according to claim 2, in which spring means are provided for holding the slide in adjusted position.

4. An electrical switch comprising a housing having a perforation and a slot therein, a resiliently mounted push button con-

tact depressible through said perforation, a finger piece reciprocable in said slot, and a slide rigidly secured to said finger piece and having an opening normally disposed beneath said push button.

5. The invention according to claim 4, in which the housing is provided with rounded elevations and the slide carries a spring member adapted to snap into such elevations.

6. An electrical switch comprising a resiliently mounted contact normally depressible to engage a conductor, a reciprocable member, movable independently of the contact, and adapted in one position to prevent depression of the contact and in another position to hold the contact continuously depressed, and spring means carried by the reciprocable member for holding it in its adjusted positions.

7. The invention according to claim 6, in which the spring means comprises a resilient arm adapted to engage cooperating means upon the housing.

8. A portable battery operated lamp comprising a casing having an opening in a wall thereof, an escutcheon plate secured to the casing adjacent said opening and having a housing overlying the same, a resiliently mounted push button depressible with respect to said housing, means secured to the housing and partly closing its base, and a member slidable upon such means and adapted to lock the push button.

9. The invention according to claim 8, in which the push button is provided with an extended portion, and the slidable member is movable beneath such portion to hold the button in elevated position.

10. The invention according to claim 8, in which the push button is provided with an extended portion the slidable member may be adjusted to rest upon the extended portion, when the button is depressed, and retains the same in depressed position.

11. The invention according to claim 8, in which a conductor strip is carried by the base closing means.

12. The invention according to claim 8, in which a conductor strip is carried by but insulated from the housing and is extended therefrom to engage a metal part in circuit with a terminal of a lamp bulb.

13. In an electrical switch for portable battery operated lamps, the combination with a conductor strip, of a circuit controlling device carrying said strip and comprising a movable circuit controlling member operable to move against and away from said strip to close and open the electrical circuit therethrough.

14. In combination with a circuit controlling device having a housing carrying a depressible contact, an arm secured to said housing, a conductor strip, and clamping

means on said arm holding said strip with one of its ends positioned beneath said depressible contact.

15. A portable battery operated lamp comprising a metal casing, a reflector insulated therefrom, a metallic circuit controlling device mounted on said casing, and a conductor strip carried by said device and adapted to engage the reflector, said device comprising a member movable against and away from said strip to close and open the electrical circuit through the latter.

16. In an electrical switch for portable battery operated lamps, the combination of a conductor, a reciprocable member having an opening therethrough, a resiliently mounted contact depressible through said opening to engage said conductor, a casing

carrying said member and enclosing said contact, and means in said casing movable by said member into a position to hold said contact continuously depressed against said conductor.

17. The combination with a casing having an opening in a wall thereof; of an apertured escutcheon plate secured to said casing over said opening; a conductor secured to the inner side of said plate and extending through said opening into said casing; and a push button carried by said plate and depressible through the aperture therein to close a circuit through said conductor.

In testimony whereof, I affix my signature.

ARTHUR J. BRIGGS.
